UNITED STATES PATENT OFFICE.

FRED D. HARPER, OF WOONSOCKET, RHODE ISLAND, ASSIGNOR TO EUGENE H. TAYLOR AND GEORGE E. GOODING, OF LYNN, MASSACHUSETTS.

FEEDING DEVICE FOR PAPER-BOX-MAKING MACHINES.

SPECIFICATION forming part of Letters Patent No. 498,976, dated June 6, 1893.

Application filed August 23, 1892. Serial No. 443,873. (No model.)

To all whom it may concern:

Be it known that I, FRED D. HARPER, of Woonsocket, county of Providence, State of Rhode Island, have invented an Improvement 5 in Feeding Devices for Paper-Box-Making Machines, of which the following description, in connection with the accompanying drawings, is a specification, like letters and figures on the drawings representing like parts.

10 This invention has for its object the improvement of paper box making machines, and relates more especially to improvements in the blank feeding mechanism.

15 My improvements are illustrated in connection with the machine such as shown in United States Patent No. 418,690, granted to Cushman and Taylor, and to which reference may be had. In the machine shown in the said patent the blanks were fed one after the other 20 from the bottom of a pile of blanks by a feeder which pushed the said blanks forward along narrow tracks, and if there were no variation in the thickness of the blanks they were properly fed into position to be acted upon by the 25 "box former" and bent into shape. If in said machine, which is sometimes the case, a blank thicker than the average is presented to the feeder it will be caught against the end gage and be crushed or torn; and the occurrence 30 of a thinner blank will allow the feeder to engage not only the lowermost blank but the next one above it also, in which event one or both blanks are spoiled and the machine is stopped.

35 In this my invention I have devised means for positioning and feeding the blanks one after another, so that no matter whether the bottom blank of the pile be thicker or thinner than the others, it alone will be fed, 40 properly and without injury to itself or stoppage of the machine, and accordingly I have devised an automatically operating gage finger to co-operate with the leading end of and adapt itself to the thickness of the blank to 45 be fed.

Figure 1, in side elevation and partial section represents a sufficient portion of the feeding mechanism of a paper box making machine with my improvements applied

thereto to enable my invention to be understood. Fig. 2, in vertical section, enlarged, shows the end gage finger forming part of my invention; and Figs. 3, 4 and 5, are details to be referred to.

The feeding frame B⁴, feeder B⁵ connected therewith and having its forward end beveled at 2, guide D, guide-rods D', D^X, stops a³ adjustably connected to the guide D by screws a², the head a⁵ having the rod a⁶, and the bearing a⁸ forming part of a bracket are and may 55 be the same as the correspondingly lettered parts in the patent, No. 418,690, referred to. The feeding frame B⁴ having the feeder B⁵ connected therewith, as stated, is reciprocated by or through arms B³, only one of which is 60 herein shown, said arms being the same as the correspondingly lettered parts in the patent referred to, and being slotted at their upper ends to embrace pins 200 secured to and projecting from the sides of the frame B⁴, one 65 of the pins being herein shown by dotted lines, the same forming no part of this my invention. The front face of the head a⁵ is 70 vertically grooved to receive the back of the end gage or finger a, shown as a vertical bar 75 held in place in said head by gibbs a', through which are extended suitable screws, only one of said gibbs being shown, see Fig. 1, said gage being vertically adjustable in the head a⁵ by means of a screw a¹⁰, and collar a¹¹ thereon 80 engaging a recessed eye or collar a¹², see Fig. 1, at the back of the end gage a, the threaded portion of the screw entering the top of the head a⁵, rotation of said screw raising or lowering the end gage a as desired. In this my 85 invention the lower end of said end gage is beveled at b, see Figs. 1 and 2, upwardly and away from its front edge 3 in the direction of the feed of the blank, and has applied to it a gage-plate b', the said plate being represented 90 as slotted longitudinally at b², see Fig. 5, and as held thereon loosely by screws c, c', extending through said slot into the end gage, the rearmost end of the said gage-plate being 95 acted upon, as shown, by a suitable spring d, shown as a flat spring secured to the back of the end gage at d' by a suitable screw, and the gage-plate is shown as slotted at b³ to

receive the spring. The gage-plate b' is adapted to slide on the beveled part of the end gage against the action of the spring, by pressure upon its lower forward edge, the 5 end gage being thus a diagonally or upwardly movable gage, it being guided in its movements and retained in position by the slot b^2 and screws c, c' , the latter also limiting the extent of longitudinal movement of the gage- 10 plate, the spring d acting upon said gage-plate to keep it normally in its full line position, Fig. 2.

A bar e is attached to the feeder B^5 immediately back of its beveled end 2, see Fig. 1.

15 Upon the upper side of the feeder B^5 at its rear end, I have adjustably secured by a set screw f an auxiliary feeding device, it being shown as a thin plate f' longitudinally slotted at f^2 , the screw f extending through the slot 20 and entering the feeder B^5 . This plate f' is so adjusted with relation to the bar e and the width of the blank, that when the feeder B^5 is in its extreme forward position, shown in Fig. 1, the forward edge of the auxiliary feeder 25 will have engaged the bottom blank of the pile of blanks C , and pushed it slightly forward, as shown best in Fig. 1, so that the leading edge of the said blank will be beyond the gage-plate b' , the thickness of the plate f' 30 being less than the thickness of an average blank, the feeder B^5 being shown in Fig. 1 as simultaneously discharging a blank f^4 from in front of the bar e . When the feeder B^5 is moved back into its starting position, the bar 35 e will be carried back beyond the rear edge of the bottom blank, but not beyond the rear edges of the blanks above it, and accordingly, when the forward movement of the feeder B^5 takes place the bar e can engage only the edge 40 of the bottom blank previously pushed forward by the auxiliary feeder, thus making it impossible for more than one blank to be fed forward at a time.

The feeder B^5 is reciprocated by means of 45 the arms B^3 , shown in Fig. 1, the slotted upper ends of said arms engaging pins, see dotted lines Fig. 1, secured to the feeding frame B^4 .

Referring now to Fig. 2, m in full lines represents a blank supposed to be of average thickness, while n , in dotted lines, represents a blank thicker than the average. The end gage a is so adjusted vertically that its lower edge 3 will admit thereunder the thickest 50 blank that may be in the pile, the lower forward edge of the upwardly sliding gage-plate b' being of such thickness that the opening left below it is sufficiently high to freely admit a blank of average thickness. Should a 55 blank of the maximum thickness be presented, its leading end will impinge against the edge of the yielding gage-plate b' and cause it to slide upwardly and forward over the beveled end b of the end gage a , against the action of 60 the spring d , until the said gage-plate has taken the position shown by dotted lines Fig.

2, when the blank will slip past the edge of the foot and be carried forward by the feeder. As soon as the rear end of the blank has been carried beyond and away from the gage-plate, 70 the latter will slide back into its normal full line position, under the action of the spring d . It will thus be seen that by first moving the bottom blank forward a short distance by the auxiliary feeder or plate f , that blank only 75 can be engaged by the bar e of the feeder B^5 upon its return to starting position, said bar not being retracted far enough to engage any of the blanks above the bottom one, so that whether it be thicker or thinner than the average, only one blank, and that the bottom one, can be fed at a time, and further, by the employment of the yielding gage-plate on the end gage, thicker blanks will not be stopped 80 thereat as they are being fed. 85

Having described my invention, what I claim, and desire to secure by Letters Patent, is—

1. In a machine for the manufacture of paper boxes, an end gage provided with a yielding gage-plate to prevent more than one blank being fed forward at a time, and to accommodate blanks of different thicknesses, combined with a feeder to strike against the rearmost edge of the blank and carry it away from the pile of blanks, and an auxiliary feeding device to move the blank forward before it is engaged by the feeder, substantially as described. 90

2. In a machine for the manufacture of paper boxes, a vertically adjustable end gage, and a spring-controlled gage plate for said end gage, combined with a feeder to strike against the rearmost edge of the bottom blank of a pile and carry it therefrom, and an auxiliary feeding device to move the bottom blank forward before it is engaged by the feeder, substantially as described. 100

3. A head, a gage vertically adjustable therein and having its lower end beveled, a sliding gage plate movable on said end, and a spring to move said gage plate in one direction, combined with a feeder to strike against the rearmost edge of the bottom blank of a pile and move it under said end gage, the sliding plate thereof being engaged and moved more or less upon the beveled end of the gage by blanks of different thicknesses, substantially as described. 110

4. In a machine for the manufacture of paper boxes, a gage to prevent more than one blank from being fed forward at a time, combined with a feeder for the blank, and an adjustable auxiliary feeding device to engage and move the bottom blank of a pile out 120 therefrom a short distance before it is engaged by the feeder, and means to adjust the auxiliary feeding device with relation to the feeder, substantially as described. 125

5. A head, an end gage vertically adjustable therein, and having a yielding gage-plate to act upon the blanks one at a time, com- 130

5 bined with a feeder to strike against the rear-most edge of a blank and carry it from the pile, and an auxiliary feeding device adjustably connected to said feeder, to engage and move the blank forward slightly before it is engaged by the feeder, substantially as described.

In testimony whereof I have signed my name to this specification in the presence of two subscribing witnesses.

FRED D. HARPER.
